240,201

TONER PARTICLE STORAGE CONTAINER

Donald R. Avolio, Fairport, Edmund G. D'Emilio, Rochester, Claude H. Hutcheson, Jr., Fairport, and Eugene A. Mikolas, Webster, N.Y., assignors to Xerox Corporation, Stamford, Conn.

Filed Mar. 30, 1973, Ser. No. 346,486

Term of patent 14 years

Int. Cl. D9—01

U.S. Cl. D9—216

FIG. 1

FIG. 2

FIG. 3

FIG. 4

FIG. 5

FIG. 1 is a left end perspective view of a toner particle storage container showing our new design;

FIG. 2 is a right end perspective view;

FIG. 3 is a front elevational view;

FIG. 4 is a left end elevational view; and

FIG. 5 is a right end elevational view.

We claim:

The ornamental design for a toner particle storage container, substantially as shown and described.
